UNITED STATES PATENT OFFICE

2,096,413

MULTIPLE JET CARBURETOR

Ira T. Swartz and Arthur R. Baker, Indianapolis,
Ind., assignors to Columbia Carburetor Com-
pany, Washington, D. C., a corporation of Del-
aware

Application March 20, 1933, Serial No. 661,817
Renewed January 7, 1936

10 Claims. (Cl. 261—12)

This invention relates to carburetors and its object is to provide a carburetor having a plurality of fuel jets and Venturi throats and also to provide automatically operable mechanism responsive to pressure conditions and to load and speed demands made upon the engine for controlling the fuel mixture supplied to the engine.

Many of the structural elements are similar to those shown in my patent No. 1,877,117, dated September 13, 1932. Other features are common to the copending application of Arthur R. Baker, Serial No. 661,809 filed of even date herewith for carburetor with choke control.

The carburetor of the present application by reason of the plurality of fuel nozzles is especially adapted for use with large displacement engines, particularly with engines which demand a larger supply of motor fuel than may be ordinarily supplied by the usual carburetor having a single fuel jet and also in small displacement engines where automatic nozzle control is desirable due to altitude variations.

Referring to the accompanying drawings, which are made a part hereof and on which similar reference characters indicate similar parts,

Figure 1 is a plan view of a portion of the carburetor.

Figure 2, a section on line 2—2 of Figure 1 with some elements omitted to avoid confusion,

Figure 3, a section on line 3—3 of Figure 2,

Figure 4, a plan view similar to Figure 1 of a modified form having two spray nozzles and two barrels, and

Figure 5, a similar plan view having two spray nozzles delivering into a single hot cap and having a single barrel or air intake.

Since the present application is an improvement over the carburetor shown in the patent and in the application referred to only so much of the structure will be shown in the present application as is necessary to illustrate the improved features, reference being made to the above mentioned patent and application for further details of the common subject matter.

In Figure 1 two hot caps 10 and 11 extend into the exhaust chamber 12 from the internal combustion engine. The nozzles are alike in structure so it will be necessary to describe but one. The hot cap 11 is shown broken away and a needle valve 13 is shown positioned adjacent a valve seat 14. Fuel is sprayed through the opening 14. Fuel is drawn through the annular passage 9 between the needle valve stem 13 and the tube 8. Air is drawn through the annular passage 7 between tube 8 and the tube 6 which extends into

the hot cap. The needle valve 13 is adjustable toward and from the valve seat by a screw cap 15. The screw cap 15 is screw-threaded upon the valve stem 13, rotation of the screw cap serving to move the valve stem toward and from its seat. The screw cap 15 is rotated by means of an arm 16 secured upon its outer end to which arm is attached a link 17. This link at its outer end is secured to a diaphragm 18 positioned to close one side of a chamber 19. A spring 20 acts against the inner side of the diaphragm to balance atmospheric pressure against the outer surface of the diaphragm. As will be apparent changes in atmospheric pressure will vary the pressure on the diaphragm. This pressure in turn is converted into rotary motion of the screw cap 15 to adjust the valve stem toward and from the valve seat. The purpose of this adjustment is to decrease the amount of fuel sprayed into the hot cap in proportion to a decrease in air pressure. At high elevations the pressure of the air is materially less than at sea level. A given volume of air at a high elevation therefore contains less oxygen than the same volume at sea level. The barometric control cuts off the supply of fuel in proportion to the decreased pressure of air which is equivalent to saying that the fuel is varied directly in proportion to the density of the air. The screw cap 21 controls a valve stem similar to 13 and this screw cap is manually operable by means of an arm 22 attached to the screw cap to which arm a link 23 is attached. The link 23 may be operated directly from the point of control of the engine, operation being either manual or otherwise. The mixture of air and motor fuel which has been heated in the hot caps 10 and 11 passes through ports 24 and 25 into a bore 26 in a tube 27 which is threaded into the carburetor casing. This tube has an enlarged end having a conical surface 28 against which air entering through the chamber 29 is deflected outwardly. An inwardly extending ridge 30 on a sleeve 34 cooperates with surface 28 to form a Venturi passage for air entering through chamber 29. Air passing through the throat formed between 28 and 30 aspirates the rich motor fuel passing through radial ports 31 and space 32 delivering it into the chamber 33 where it passes to the engine. The throttle opening between 28 and 30 is controlled by vertical movement of the sleeve 34. This sleeve may be manually operated in any suitable way such as by the mechanism shown in the patent or the application referred to. Means are provided as in the other application for supplying an additional volume

of motor fuel to the chamber 29 as the sleeve 34 is depressed beyond a predetermined distance. This fuel is supplied through a tube 35. This tube communicates with the atmospheric pressure at 5 36 and liquid fuel from the cup enters through the valve 38 into the tube 35 being mixed with the air entering from outside the carburetor at 10 36. The valve 39 is urged against its seat by means of a spring 40. The valve is tapered as 15 shown at 41 so that the amount of fuel supplied is gradually increased as it is further depressed by the sleeve 34. Means are provided for automatically choking the air to increase the supply of motor fuel in proportion to air to start the 20 engine. These consist of butterfly valves 42 and 43 which are pivoted off center on shafts 44 and 53 respectively. Shaft 44 carries an arm having a pin 45 therein which pin engages normally against the side of a slotted arm 46 which arm 25 is loosely mounted on the shaft 44. A link 47 is pivotally attached to the slotted end of the arm 46 and this link 47 carries on its outer end a piston and sealing cup 48 which cup is slidable in cylinder 49. The cylinder is closed by a cap 50 which is threaded into its open end and a light 30 spring 51 surrounds the link 47 having one end in engagement with the cap 50 and the other end engaging the inner side of the piston 48. The end of the cylinder adjacent piston 48 is provided 35 with an air port 52. An arm 54 is attached to shaft 53. Extending through the side of the carburetor casing is a fuel and air tube 55 similar to tube 35. Tube 55 is open to atmosphere through a port 56. To the tube 55 there is connected a motor fuel port 57 which is normally closed by a valve 58 which is urged upon its seat by spring 59. When the valve 58 is depressed fuel is allowed to flow through valve port 57 into the tube 55 through which it is drawn into the 40 suction chamber 29 where it is mixed with the air passing through the Venturi throat. The valve 58 is connected by means of a link 60 with the arm 54.

In operation fuel is supplied to the engine 45 through either or both of the nozzles through ports 24 and 25. This fuel is mixed with a relatively large volume of cold air coming in through the chamber 29. When the engine is first started, suction through the tube 29 will cause butterfly valve 43 to pivot on its shaft 53 counter-clockwise. The first result of this movement of the butterfly valve will be to pull down the valve 58 and admit motor fluid through the valve port 57 where it mixes with air coming through the tube 55 and the air which enters through opening at 50 the butterfly valve 43. The addition of raw fuel into the air stream from fuel port 57 enriches the fuel mixture at the starting of the engine. Suction in the chamber 29 also causes the butterfly valve 42 to open, pivoting in a clockwise direction. Movement of this valve is resisted by the vacuum created at the head of the cup washer 48. The vacuum is slowly broken, however, by air which issues through the port 52. Butterfly 55 valve 42 therefore will open somewhat after butterfly valve 43 has opened. As soon as valve 42 is fully or even partially open valve 43 will close or tend to close under influence of spring 59 which is of greater tension than spring 51. The auxiliary fuel supply delivered to chamber 29 through tube 55 will therefore be cut off. Valve 42 will move to fully open position and will be maintained in this position by the engine suction. The spring 51 will be only strong enough 70 to restore the cup 48 to its original position after 75

the engine stops. The opening of the valve 42 will be maintained in varying degree according to the volumetric requirement of the engine with a minimum of back pressure.

In the form shown in Figure 4 there are two 5 hot caps 61 and 62 each having valves extending therein, which valves may be operated by screw caps 63 and 64 in the manner described in Figure 1. A mixture of motor fuel and air from the hot caps 61 and 62 goes each to its respective air inlet barrel 65 and 66 and from these barrels fuel passes through openings 67 and 68 into the suction stream of the engine. In this form the mixture of air and motor fluid follows two separate paths so as to form in effect a double 15 carburetor or double fuel supply for the engine. The form shown in Figure 4 includes the valve assembly shown at the bottom of Figure 2.

In the form shown in Figure 5 the nozzles spray 20 the fuel into a single hot cap 69 and from this 25 hot cap the rich mixture of motor fuel and air is delivered to the Venturi throttle where it is mixed with cold air in the usual way. Each of the forms shown in the present application provides 30 means which may be operated to supply motor fuel and air in relatively large volumes such as are required for operation of large vehicles such as busses, trucks and the like. The form shown in Figure 5 includes also the valve assembly shown 35 at the bottom of Figure 2.

It will be obvious to those skilled in the art 40 that various changes may be made in our device without departing from the spirit of the invention and therefore we do not limit ourselves to what is shown in the drawings and described in the specification, but only as indicated by the appended claims.

Having thus fully described our said invention, 45 what we claim as new and desire to secure by Letters Patent, is:

1. In a carburetor having a plurality of hot caps and a fuel spray nozzle extending into each of such hot caps, manually operable means for adjusting some of said spray nozzles, and means responsive to changes in atmospheric pressures 45 for adjusting other spray nozzles whereby the fuel mixture may be automatically or manually controlled in proportion to air density, substantially as set forth.

2. In a carburetor having a plurality of hot 50 caps, a fuel nozzle delivering into each of said hot caps, manual means for adjusting one of said fuel nozzles and means responsive to variation in air pressure for adjusting the other nozzle and a Venturi throttle for each of said hot caps 55 for controlling passage of fuel from each of said hot caps to the engine, substantially as set forth.

3. A carburetor having a single hot cap positioned in the path of the exhaust gases from the engine, a pair of fuel spray nozzles each positioned to direct fuel into said hot cap and for mixing it with air therein, and a single Venturi 60 throttle for controlling the passage of fuel from said hot cap to said engine, substantially as set forth.

4. In a carburetor for an internal combustion engine having an air intake for supplying air to a fuel mixture, a plurality of butterfly valves positioned adjacent each other to close off said air intake said butterfly valves being pivoted 70 off center whereby passage of air through said intake will tend to open said valves, and means operated by one of said valves for supplying additional motor fuel to said air supply at the start of the engine, substantially as set forth.

5. In a carburetor having an air intake passage for supplying air to the fuel mixture, a pair of butterfly valves controlling said air intake passage, one of said butterfly valves operating to supply additional motive fluid to said air, the other butterfly valve being retarded in its action but opening under engine suction, opening of said last named butterfly valve permitting the first named butterfly valve to close to cut off the additional supply of motor fuel to the air stream, substantially as set forth. 5
10. In a carburetor of the kind described, means for making an initial fuel-air mixture, means responsive to barometric changes for determining the richness of said mixture, means for making an additional fuel-air mixture, and means responsive to load, velocity and accelerating demands for determining the quality of said second fuel-air mixture, substantially as set forth. 10
15. 7. A carburetor of the kind described adapted to deliver a relatively heavy fuel charge comprising fuel nozzles for making an initial fuel air mixture, means for heating said mixture at the point of mixing, means responsive to variation 20 in air pressure for controlling some of said fuel air means to determine the richness of the mixture, means for adding additional fuel air mixtures to the mixtures already made in response to load velocity and accelerating demands for 25 30 determining the quantity of the said second fuel air mixture. 30
8. In a carburetor of the kind described, means for supplying a relatively large volume of fuel and air heated to a relatively high temperature, 20
- a pair of butterfly valves for controlling the supply of scavenging air to said fuel mixture, one of said valves being in control of an additional fuel supply means and the other of said valves being responsive to load demands to throttle off the air at the beginning of speed acceleration and later opening to supply air in the correct proportions for normal operating speed and load. 25
9. In a carburetor of the kind described, means for supplying a relatively large volume of fuel and air heated to a relatively high temperature, 10 means for supplying additional air to said rich hot body of fuel and air and means for supplying additional raw fuel to said additional air at the starting of the engine and for reducing the 15 amount of said additional fuel as the engine comes to full speed. 15
10. Means for forming a fuel charge for an internal combustion engine comprising a chamber positioned in heat exchange relation with hot exhaust gases from the engine, means for supplying fuel and air to said chamber to be mixed and heated therein, means responsive to changes in atmospheric pressure for controlling the amount of fuel in proportion to air delivered to said chamber, means for supplying additional air to said mixture after the heating of the mixture and means for automatically supplying additional fuel at the moment of starting and increase of speed demands for fuel. 20 25 30
